UNITED STATES PATENT OFFICE

JAMES W. MUNDY AND GEORGE E. BOHANNON, OF BALTIMORE, MARYLAND

ANTENNA SUPPORT

Application filed April 30, 1930. Serial No. 448,653.

This invention relates to an antenna support of that type for positioning on roofs constructed of sheet metal plate provided with interlocking flanges, and has for its object to provide, in a manner as hereinafter set forth, a support of the class referred to capable of being secured in a stationary manner upon the roof without impairing the latter to any extent whatsoever.

10 A further object of the invention is to provide, in a manner as hereinafter set forth, an antenna support for positioning upon roofs constructed from sheet metal plates provided with interlocking flanges and with the support so constructed and arranged whereby it is secured in an upright position relative to the roof without the employment of holdfast devices such as nails, which impair the roof to an extent to result in leakage.

20 A further object of the invention is to provide, in a manner as hereinafter set forth, an antenna support for positioning on roofs constructed of sheet metal plate provided with interlocking flanges and with the antenna support including means to permit of the adjustment thereof to enable it to be employed in a satisfactory manner upon sloping roofs.

Further objects of the invention are to provide, in a manner as hereinafter set forth, 30 an antenna support which is simple in its construction and arrangement, strong, durable, compact, adjustable, thoroughly efficient in its use, conveniently set up, readily assembled and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope 40 of the claims hereunto appended.

In the drawings wherein like reference characters denote corresponding parts throughout the several views:—

Figure 1 is an elevation of an antenna support in accordance with this invention and 50 illustrating an antenna connected therewith and further the support positioned upon a roof formed of interlocking metallic sheets.

Figure 2 is a top plan view of a pair of antenna supports in accordance with this invention showing the adaptation thereof with respect to an antenna, the latter being broken away and also showing the supports mounted upon a roof constructed of interlocking flanged metallic sheets, the roof being broken 60 away.

Figure 3 is a fragmentary view partly in section and in side elevation illustrating the base of the support mounted upon the roof.

Figure 4 is a section on line 4—4, Figure 3. 65

Figure 5 is a side elevation of one of the guy ropes, cable or wire coupling members showing the adaptation thereof with respect to the interlocking flanges of a pair of metallic plates from which the roof is formed. 70

Figure 6 is a section on line 6—6, Figure 5.

An antenna support, in accordance with this invention, includes a rectangular base 1 formed from any suitable material, preferably wood. The base 1 is of the desired height 75 and is also of a length greater than the distance between a pair of interlocking spaced, opposed flanges 2, 3 of the metal plates of the roof 4. The base 1, centrally of its upper face, is formed with a socket 5 of a depth less than 80 the height of the base 1. Mounted in the socket 5 is a post 6 formed of any suitable material and of the desired height. The base 1 in proximity to each end thereof has its lower face provided with a transverse groove 85 7 having a convexed top wall 8. The distance between the grooves 7 is such that when the base 1 is mounted in position the grooves will be arranged over and in alignment with the interlocked flanges 2, 3. 90

The base 1 in proximity to each end thereof is formed with a pair of vertically disposed, aligning spaced openings 9, 10 which terminate at their lower ends in the grooves 7. Extending upwardly through the openings 9, 10 are bolts 11, 12 respectively. The heads 13 of the bolts are arranged at the lower ends of the latter. The bolts extend a substantial distance above the upper face of the base 1 and carry washers 14 and clamping nuts 15.

Associated with each pair of bolts and extending into a groove 7 is an inverted, U-shaped connecting member 16 of a length greater than the width of base 1 and which projects a substantial distance beyond each side face of base 1. The coupling member is mounted on an interlocking flange 2 or 3 and is formed at its bottom with oppositely extending flanges 17. The top of the connecting member 16 at a point between its vertical median and one end is formed with an opening 18' and at a point between its vertical median and its other end is provided with an opening 19'. The bolts 9, 10 extend upwardly through the openings 18', 19' respectively and the heads 13 of the pair of bolts abut against the inner face of the top of the connecting member 16. The convexed wall 8 seats on the upper face of the top of the connecting member 16 and permits of the base 1 being secured level or squared with respect to the interlocking flanges 2 or 3 when the flanges incline downwardly in either direction. The connecting member 16 will extend in the same direction as the interlocking flanges 2 or 3, but when the base 1 is clamped to member 16 it will be arranged level, and this level position is had at all times by the convexed walls 8 in connection with the bolts 9 and 10, as one of the bolts will extend a greater distance above the base 1 to clamp a portion of the walls 8 against members 16 to secure base 1 in level position. With respect to the manner in which the convexed walls 8 and bolts 9, 10 function to maintain the base 1 level when it is mounted on a sloping roof attention is directed to Figure 4.

The support includes a series of coupling members and a series of guy wires, and by way of example, each series is shown as consisting of four coupling members or guy wires, but this number can be decreased if desired. As shown, the coupling members and guy wires are arranged in pairs. One pair of coupling members is spaced rearwardly from the base 1 and one pair of guy wires extends rearwardly from post 6. The other pair of coupling members is spaced forwardly of base 1 and the other pair of guy wires extend forwardly from post 6. The guy wires are disposed at an inclination with respect to post 6 and have their other ends secured to post 6 near its upper end as at 17'. The guy wires which extend forwardly from post 6 are indicated at 18 and the guy wires

which extend rearwardly from post 6 are indicated at 19. The coupling members which are spaced forwardly from base 1 are indicated at 20. The coupling members which are arranged rearwardly from base 1 are indicated at 21. The guy wires 18 extend rearwardly and at an upward inclination from the coupling members 20. The guy wires 19 extend forwardly and at an upward inclination from coupling members 21. Each guy wire can be a wire, cable or rope, or a thin chain and which is termed a bracing element. Each guy wire has its lower end fixedly secured to a coupling member.

Each coupling member consists of an oval-shaped, hollow body portion 22 split at its bottom as at 23 and formed of resilient material. The body portion 22 is reinforced by an outwardly directed flange 24 at each side thereof. The sides of the body portion 22 are indicated at 25, 26 and are formed with aligning openings 27. Extending through the aligning openings 27 is a headed clamping bolt 28, which carries a clamping nut 29. The interlocked flanges of the metallic sheets from which the roof 4 is provided are formed with an overlapped part, indicated at 30. Figure 6, and which is of less height than the height of the joint when it is completed. The overlapped part 30 provides a ridge or shoulder 30 on one side of the interlocked flanges and said shoulder 30 is spaced a distance above the upper face of the roof 4. See Figure 6. The interlocked flanges are extended up into the body portion 22 and one side of the latter engages under the shoulder 30. As illustrated in Figure 6 the free end of side 25 engages under the shoulder 30 and abuts one side of the joint. After the body portion 22 is in such position the nut 29 is screwed home to tightly clamp the member 24 to the interlocking flanges and which maintains the clamping member stationary. As a guy wire is connected to the coupling member it is held in bracing position relative to the pole.

The manner of connecting the support to the roof dispenses with the employment of holdfast devices generally employed for securing an antenna pole in position and such holdfast devices impair or aperture the roof and the result is that the roof begins to leak, but by setting up the support in the manner as herein stated such objection is not present. The base 1 is positioned a substantial distance above the roof so that the passage of water thereunder is not arrested or prevented, as there is sufficient clearance for such purpose between the lower face of the base 1 and the upper face of the roof 4.

In Figure 1 of the drawings a pair of antenna supports, in accordance with this invention are generally indicated at 31, 32 and which have connected to their upper ends the antenna or aerial 33.

It is thought the many advantages of an

antenna support, in accordance with this invention and for the purpose referred to can be readily understood, and although the preferred embodiment of the invention is as illustrated and described, yet it is to be understood that changes in the details of construction can be had which fall within the scope of the invention as claimed.

What we claim is:

1. An antenna support comprising a base having spaced grooves in its lower face and a socket in its upper face, said base adapted to be arranged over and disposed transversely with respect to a pair of spaced interlocking flanges of a metallic roof, a pole mounted in said socket and adapted to be connected to one end of an antenna, a pair of connecting members adapted to be mounted in overlapping relation with respect to said pair of flanges, said members opposing said grooves, means for adjustably attaching said members to said base, coupling members spaced from said base and adapted to be clamped to and extend above said flanges, and guy wires connected at one end to said coupling members and at the other end to said pole in proximity to the upper end of the latter.

2. An antenna support comprising a base having spaced grooves in its lower face and a socket in its upper face, said base adapted to be arranged over and disposed transversely with respect to a pair of spaced interlocking flanges of a metallic roof, a pole mounted in said socket and adapted to be connected to one end of an antenna, a pair of connecting members adapted to be mounted in overlapping relation with respect to said pair of flanges, said members opposing said grooves, means for adjustably attaching said members to said base, coupling members spaced from said base and adapted to be clamped to and extend above said flanges, and guy wires connected at one end to said coupling members and at the other end to said pole in proximity to the upper end of the latter, the top wall of each of said grooves being convexed, said means extending into said grooves.

3. An antenna support comprising a base having spaced grooves in its lower face and a socket disposed centrally of its upper face, said base adapted to be disposed in superposed, spaced relation with respect to a pair of spaced interlocking flanges of a metallic roof and of a length greater than the distance between said flanges, a pole mounted in said socket and adapted to have one end of an antenna connected thereto, a pair of inverted, U-shaped connecting members adapted to be mounted in overlapping relation with respect to said flanges, said members opposing said grooves, means extending through said base for adjustably attaching said members thereto in opposed relation with respect to said grooves, coupling members spaced from said base, adapted to receive said flanges and in-

cluding means for clamping them to said flanges in fixed relation with respect thereto, and guy wires connected at their lower ends to said coupling members and at their upper ends to said pole in proximity to the upper end of the latter.

4. An antenna support comprising a base having spaced grooves in its lower face and a socket disposed centrally of its upper face, said base adapted to be disposed in superposed spaced relation with respect to a pair of spaced interlocking flanges of a metallic roof and of a length greater than the distance between said flanges, a pole mounted in said socket and adapted to have one end of an antenna connected thereto, a pair of inverted, U-shaped connecting members adapted to be mounted in overlapping relation with respect to said flanges, said members opposing said grooves, means extending through said base for adjustably attaching said members thereto in opposed relation with respect to said grooves, coupling members spaced from said base, adapted to receive said flanges and including means for clamping them to said flanges in fixed relation with respect thereto, and guy wires connected at their lower ends to said coupling members and at their upper ends to said pole in proximity to the upper end of the latter, the top walls of said grooves being convexed and seating on the top of said connecting members.

5. An antenna support comprising a base having spaced grooves in its lower face and a socket in its upper face, said base adapted to be positioned in superposed spaced relation with respect to a pair of spaced interlocking flanges of a metallic roof and of a length greater than the distance between said flanges, a pole mounted in said socket, inverted, U-shaped connecting members of greater length than the width of said base and adapted to be arranged in overlapping relation with respect to said flanges, means extending through said base and into said grooves for adjustably connecting said members to said base in opposed relation with respect to the grooves, and inclined bracing means connected at the upper ends thereto to said pole and having their lower ends clamped to said flanges adjacent said base.

6. An antenna support comprising a base having spaced grooves in its lower face and a socket in its upper face, said base adapted to be positioned in superposed spaced relation with respect to a pair of spaced interlocking flanges of a metallic roof and of a length greater than the distance between said flanges, a pole mounted in said socket, inverted, U-shaped connecting members of greater length than the width of said base and adapted to be arranged in overlapping relation with respect to said flanges, means extending through said base and into said grooves for adjustably connecting said mem-

bers to said base in opposed relation with respect to the grooves, and inclined bracing means connected at the upper ends thereto to said pole and having their lower ends clamped to said flanges adjacent said base, the top walls of said grooves being convexed and seating intermediate its ends on the top of such members.

In testimony whereof, we affix our signatures hereto.

JAMES W. MUNDY.
